UNITED STATES PATENT OFFICE

159,574

TELEVISION CABINET

Samuel E. Adler, Chicago, Ill.

Application May 5, 1949, Serial No. 2,453

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet of which the following is a specification, reference being had to the accompanying drawing, forming part thereof.

Fig. 1 is a perspective view showing the top, front and side panels of a television cabinet showing my new design, the doors thereof being closed.

Fig. 2 is a similar view thereof, the doors being open.

The dominant features of my design reside in that portion shown in full lines in the drawing.

I claim:

The ornamental design for a television cabinet, as shown and described.

SAMUEL E. ADLER.
